CLAIM

The ornamental design for a virtual reality terminal helmet, as shown and described.

DESCRIPTION

FIG. 1 is a front view of a virtual reality terminal helmet according to the present application;
FIG. 2 is a rear view of the virtual reality terminal helmet according to the present application;
FIG. 3 is a left view of the virtual reality terminal helmet according to the present application;
FIG. 4 is a right view of the virtual reality terminal helmet according to the present application;
FIG. 5 is a top view of the virtual reality terminal helmet according to the present application;
FIG. 6 is a bottom view of the virtual reality terminal helmet according to the present application; and,
FIG. 7 is a perspective view of the virtual reality terminal helmet according to the present application.
